CATALYTIC CRACKING OF DIISOBUTYLENE

Frank B. Johnson, Baton Rouge, La., assignor to
Standard Oil Development Company, a corporation of Delaware

Application November 14, 1947, Serial No. 736,844

6 Claims. (CL 196—52)

1

This invention pertains to catalytic cracking and particularly to the catalytic cracking of diisobutylene to produce isobutylene.

The cracking of diisobutylene to produce isobutylene and the catalytic cracking of hydrocarbon oils such as gas oil to lower boiling materials such as motor fuel are well known and present no particular problems when carried out separately in equipment designed for the particular purpose under carefully controlled conditions. When, however, an attempt was made to crack diisobutylene to isobutylene simultaneously with the cracking of liquid hydrocarbons such as gas oil to motor fuels and the like, substantial difficulties were encountered. The yields of isobutylene were too low to be commercially attractive, the selectivity was relatively poor resulting in low ratios of isobutylene to other cracked products such as normal butane and isobutane from the diisobutylene. The inclusion of diisobutylene in the gas oil feed to a catalytic cracking unit also had adverse effects upon the gas oil cracking, lower yields of motor fuels were produced in some cases and in other cases, particularly with fresh or highly active catalysts, the carbon formation was appreciably greater when dimer was incorporated in the gas oil feed.

It is the object of this invention to provide the art with a novel method for cracking diisobutylene to isobutylene simultaneously with the cracking of higher boiling hydrocarbon oils such as gas oil to motor fuels.

It is also the object of this invention to so integrate the cracking of diisobutylene with the catalytic cracking of liquid hydrocarbons that the cracking of both stocks will proceed in the desired manner.

These and other objects will appear more clearly from the detailed specification and claims which follow.

I have now found that diisobutylene can be cracked to isobutylene simultaneously with the catalytic cracking of hydrocarbon oils to motor fuels in the same reaction equipment provided that the cracking is effected in a fluid catalyst cracking unit, preferably one containing a relatively dense catalyst phase in the lower part of the reaction vessel and a disperse or dilute catalyst phase in the upper portion of the reaction vessel. I have found that if the diisobutylene is introduced into the reaction vessel at or closely adjacent the dense bed-disperse phase interface it can be cracked at high conversions and with good selectivity and without any adverse effects upon the cracking of the gas oil or other liquid hydrocarbon.

In the drawing, the figure represents a diagrammatic flow plan of the process according to the present invention.

Referring now to the drawing, the reference

10 character 10 designates the reaction vessel which is cylindrical in form and provided with an inlet line 11 for introducing a mixture of hydrocarbons in vapor form or partly in vapor form and catalyst or contact particles. The hydrocarbon feed stocks can be gas oil, reduced crude oil, whole crude petroleum oil, heavy naphtha, etc. The hydrocarbon feed stock is supplied to the inlet 11 through line 12 from suitable preheating or vaporizing equipment (not shown), in liquid, in vapor or partly in liquid and partly in vapor form.

15 The catalyst or contact particles are withdrawn in heated condition from the regenerator 13 through line 14 and introduced into the inlet line 11 by means of the standpipe 15 in known manner. The heated catalyst particles serve to effect vaporization of the feed stock and bring the mixture up to reaction or cracking temperatures. The suspension of solid catalyst particles in vaporized hydrocarbons is passed upwardly 20 through line 11 into suitable distributing means 16 arranged at the bottom portion of the reaction vessel 10.

25 The distributing means 16 is provided with a horizontally disposed perforated circular plate which is arranged centrally with respect to the reaction vessel. The diameter of the perforated plate and the entire distributing means is less than the internal diameter of the reaction vessel 10 in order that an annular passageway 17 may be provided between the distributing means 16 and the wall of the reaction vessel for the withdrawal of catalyst particles. This annular passageway may be provided with suitable baffle 30 means and inlets 18 may also be provided for the supply of steam or other gaseous stripping agent to said passageway in known manner for the purpose of removing adsorbed hydrocarbon materials from the catalyst particles before they are 35 discharged from the bottom of the reaction vessel into the standpipe 19 and thence into line 20 where they are picked up by a stream of air and carried into the regenerator 13 where the carbonaceous deposits are burned off and the catalyst particles conditioned for recycling to the 40 reaction vessel 10.

45 The velocity of the hydrocarbon vapors passing upwardly into the reaction zone or vessel 10 through the perforated plate at the top of the distributing means 16 is preferably selected to maintain the solid catalyst particles in a dense, fluidized, liquid-simulating dry mixture or dense bed 21. This mobile, turbulent mass or mixture insures intimate contact between hydrocarbon vapors and the catalyst or contact particles. As the vaporous reaction products leave the dense bed 21, they entrain a small amount of solid particles forming a dilute suspension or disperse phase 22 thereabove.

50 In the catalytic cracking of hydrocarbons,

the cracking catalyst comprises any suitable cracking catalyst such as acid-treated bentonite clay, synthetic silica-alumina gel, synthetic silica-magnesia gel, synthetic silica-alumina-magnesia gel, etc. The catalyst is preferably in powdered or finely divided form in which the particles have a size between about 100 and 400 standard mesh. The preferred catalyst comprises microspherical particles of which about 95% passes through a 100 standard mesh sieve and the mixture contains less than 35% preferably about 5-10% of 0-20 micron material. With such a catalyst, the velocity of the gaseous fluid passing upwardly through the dense bed 21 is about 0.5 to 2.0 ft./second and under these velocity conditions the density of the material forming the dense bed 21 is about 5 to 40 lbs./cu. ft.

In order to crack diisobutylene simultaneously with the cracking of gas oil or other high boiling hydrocarbon, diisobutylene feed is supplied, preferably preheated to about reaction temperatures to the reaction vessel 10 through feed line 23. As shown the feed line 23 connects with three valved inlets to the reactor, the lower inlet entering the dense phase 21, the intermediate inlet entering the reactor at the interface between the dense phase and the dilute phase and the top inlet entering the dilute phase. Spray nozzle means are preferably provided on each inlet in order to effect uniform distribution of the dimer in the reactor. By selection of the appropriate inlet, the severity of the cracking conditions to which the diisobutylene is subjected can be varied, from fairly severe when introduced into the dense bed to very mild when introduced into the dilute or disperse phase 22. While I have shown but a single inlet at each of the three levels, it will be understood that a plurality of inlets may be provided at each level, that inlets at more than three levels can be provided and that further it is within the scope of this invention to introduce the diisobutylene at two or more levels simultaneously at the same or at different rates. Ordinarily I prefer to introduce the diisobutylene at the interface between the dense bed and the disperse phase. Introduction of the dimer feed at or above the interface has the further advantage of avoiding an entrainment problem. In other words if the dimer feed is added to the dense bed, the total vapor velocity through the dense bed is increased and entrainment of catalyst fines is increased whereas if the dimer is added at or above the interface the vapor velocity through the dense bed is unaffected and entrainment will be substantially the same as if no dimer was added to the system. Instead of diisobutylene per se, I may use various commercial products which contain a major proportion of diisobutylene. Typical of such products are a mixture containing 90% diisobutylene, 9% of codimer (isobutylene-n-butylene copolymer) and 1% trimer as well as mixtures containing about 65% of dimer and codimer and about 35% trimer. These materials, will be referred to hereinafter as normally liquid polymers of isobutylene.

The amount of polymer that can be injected into the disperse phase in the reactor should not exceed about 50 volume per cent based upon the high boiling liquid hydrocarbon feed stock or gas oil and preferably represents about 10-20 volume per cent.

The vaporous reaction products and entrained catalyst particles are withdrawn from the reaction vessel 10 through a cyclone separator 24

or the like which serves to separate most of the entrained solid catalyst particles. The separated solid particles are returned to the dense bed through line 25 which extends below the top surface of the dense bed 21. The vaporous reaction products leaving the separating means 24 pass overhead through line 26 whence they may be passed to any suitable fractionating equipment to recover the desired products. Any catalyst fines carried into the fractionating equipment are returned as a slurry in the recycle oil which is combined with the fresh feed and passed again through the cracking zone.

The following example is illustrative of the present invention:

A wide-cut paraffinic gas oil having a gravity of 29.8° API, 50% point of 700° F. and 1.7% of which is distilled at 430° F. was cracked in a fluid catalytic cracking unit alone and with a commercial grade of isobutylene polymer (analysis 90% dimer, 9% codimer and 1% trimer) added in the gas oil feed as well as injected directly into the reactor. The catalyst used was a synthetic silica-alumina gel catalyst containing about 12% alumina and the cracking temperature in each case was 975° F. The results obtained on these runs are summarized in the following table:

Feed Stock, Vol. Percent:	100	87.1	89.6	90.2
Gas Oil	100	87.1	89.6	90.2
Dimer	0	12.9	10.4	9.8

¹ With oil feed.

² Point of injection calculated to be about 3 in. below top of dense bed.

³ Point of injection calculated to be about 3 in. above top of dense bed.

These results show that the addition of dimer to wide-cut gas oil feed increased isobutylene 55 yield (based on gas oil feed) from 4.0 percent to about 10 per cent. On a total feed basis carbon yields are roughly the same for the gas-oil and for the gas-oil-dimer mixed feed.

Injection of the dimer into the disperse phase 60 in the reactor zone gave appreciably better results than were obtained when the dimer was added with the gas-oil feed, giving higher conversion to isobutylene, with greater selectivity (less formation of isobutane and n-butane), higher concentrations of isobutylene in the C₄ fraction and lower dry gas formation.

Gasoline yields are comparable (based on total feed) for the dimer-gas oil operation and for gas oil cracking alone. Gasoline octanes were about the same to 1.3 points higher when dimer was mixed in the feed and gasoline volatility was about the same as that obtained with straight gas oil feed showing that the combined operation has no detrimental effects upon regular gas oil cracking operations.

The foregoing description contains a limited number of embodiments of the present invention. It will be understood, however, that numerous variations are possible without departing from the scope of this invention as defined in the following claims.

What I claim and desire to secure by Letters Patent is:

1. In the method of cracking higher boiling hydrocarbons by passing them upwardly through a mass of solid contact particles which catalyst particles are maintained in a dense phase, dry fluidized liquid like condition in the lower portion of a reaction zone and in a dilute phase in the upper portion of the reaction zone, the step which comprises injecting a normally liquid isobutylene polymer into the reactor at a level not below the dense-phase dilute phase interface in order to subject said polymer to relatively milder cracking conditions than the higher boiling hydrocarbon feed stock is subjected to and to crack said polymer principally to isobutylene.

2. In the method of cracking higher boiling hydrocarbons by passing them upwardly through a mass of solid contact particles which catalyst particles are maintained in a dense phase, dry fluidized liquid like condition in the lower portion of a reaction zone and in a dilute phase in the upper portion of the reaction zone, the step which comprises injecting up to about 50 volume per cent based upon the higher boiling hydrocarbon feed of a normally liquid isobutylene polymer into the reactor at a level not below the dense phase-dilute phase interface in order to subject said polymer to relatively milder cracking conditions than the higher boiling hydrocarbon feed stock is subjected to and to crack said polymer principally to isobutylene.

3. In the method of cracking higher boiling hydrocarbons by passing them upwardly through a mass of solid contact particles which catalyst particles are maintained in a dense phase, dry fluidized liquid like condition in the lower portion of a reaction zone and in a dilute phase in the upper portion of the reaction zone, the step which comprises injecting diisobutylene into the reactor at a level not below the dense phase-dilute phase interface in order to subject said diisobutylene to relatively milder cracking conditions than the higher boiling hydrocarbon feed stock is subjected to and to crack said diisobutylene principally to isobutylene.

4. In the method of cracking higher boiling hydrocarbons by passing them upwardly through a mass of solid contact particles which catalyst particles are maintained in a dense phase, dry

fluidized liquid like condition in the lower portion of the reaction zone and in a dilute phase in the upper portion of a reaction zone, the step which comprises injecting up to about 50 volume per cent based upon the higher boiling hydrocarbon feed of diisobutylene into the reactor at a level not below the dense phase-dilute phase interface in order to subject said diisobutylene to relatively milder cracking conditions than the higher boiling hydrocarbon feed stock is subjected to and to crack said diisobutylene principally to isobutylene.

5. In the method of cracking higher boiling hydrocarbons by passing them upwardly through a mass of solid contact particles which catalyst particles are maintained in a dense phase, dry fluidized liquid like condition in the lower portion of a reaction zone and in a dilute phase in the upper portion of the reaction zone, the step which comprises injecting 10 to 20 volume per cent based upon the higher boiling hydrocarbon feed of a normally liquid isobutylene polymer into the reactor at a level not below the dense phase-dilute phase interface in order to subject said polymer to relatively milder cracking conditions than the higher boiling hydrocarbon feed stock is subjected to and to crack said polymer principally to isobutylene.

6. In the method of cracking higher boiling hydrocarbons by passing them upwardly through a mass of solid contact particles which catalyst particles are maintained in a dense phase, dry fluidized liquid like condition in the lower portion of the reaction zone and in a dilute phase in the upper portion of a reaction zone, the step which comprises injecting 10 to 20 volume per cent based upon the higher boiling hydrocarbon feed of diisobutylene into the reactor at a level not below the dense phase-dilute phase interface in order to subject said diisobutylene to relatively milder cracking conditions than the higher boiling hydrocarbon feed stock is subjected to and to crack said diisobutylene principally to isobutylene.
